UNITED STATES PATENT OFFICE.

NELSON WEEKS, JR., OF LONG ISLAND CITY, NEW YORK.

ELECTRIC SEARCH-LIGHT.

SPECIFICATION forming part of Letters Patent No. 469,050, dated February 16, 1892.

Application filed June 4, 1891. Serial No. 395,072. (No model.)

To all whom it may concern:

Be it known that I, NELSON WEEKS, Jr., a citizen of the United States, residing in Long Island City, county of Queens, and State of New York, have invented certain new and useful Improvements in Search-Lights, fully set forth in the following description and represented in the accompanying drawings.

This invention relates, generally, to electric lamps, and more particularly to those adapted for search-light purposes—that is to say, in which there is combined with the electric lamp a reflector and lens for throwing parallel rays of light to a distance or for concentrating the rays of light on a distant object.

The invention has for its object, primarily, to save all of the strongest rays of light by causing them to be received directly upon the reflecting-lens, and by it transmitted to a distance.

It also has for its object to improve the general construction of such lamp, whereby it may be manipulated with ease, either by hand or automatically, and to lessen its weight, first cost, and cost of maintenance.

To this end the invention consists in arranging the carbons of the lamp in a line parallel with the parallel reflected rays of light from the reflecting-lens, in contradistinction to arranging the carbons at right angles or substantially at right angles thereto, by which parallel arrangement substantially all of the strongest rays of light from the carbons are received directly upon the reflecting-lens.

It also consists in supporting the lamp from or upon gimbals, adapting it for service on ship board, and to maintain a substantially fixed position irrespective of the motion of the ship.

It furthermore consists in combining with the lamp a front reflector for receiving those rays of light that would be otherwise lost and transmitting them to the reflecting-lens and in making the front reflector in the form of a movable shutter that may be used for signaling purposes.

It finally consists in means for regulating the position of the lamp for directing its rays upon the distant object, either with or independent of the universal movement upon or from the gimbals, and in details of construc-

tion and combinations of parts hereinafter fully set forth.

In the accompanying drawings, which illustrate a practical embodiment of the invention in its preferred form, as well as in one of the many modifications thereof that would be readily suggested to a skilled mechanic, Figure 1 is a front view partially in vertical section. Fig. 2 is a vertical sectional elevation taken on the line 2 2 of Fig. 1, the base being omitted. Fig. 3 is a horizontal section taken on the line 3 3 of Fig. 2. Fig. 4 is an enlarged detailed section of a pair of solenoids for turning a wheel and shaft in either direction. Fig. 5 is an enlarged section of the reflecting-lens and carbons. Fig. 6 is a sectional elevation of a modified form of the lamp-frame.

Referring now more particularly to Fig. 1, it will be understood that the improved lamp A is supported or held by a suitable framework composed in the main of a yoke-bracket B, that is carried by a support or base C. The lamp proper is contained by an annular frame D, having opposite trunnions a, that find bearings in the ends of the yoke-bracket, which thus allows the annular frame, with the lamp, to swing to any position either side of its vertical plane. The yoke-bracket B is provided with a central stem b, that is received and supported by a pendant c, in which it is adapted to turn or rotate horizontally, resting at its upper end upon a ball-bearing d. The pendant in turn is carried by a pair of gimbals e, the outer one of which is immediately supported in the upper end of the base C. The base C is of hollow, cylindrical, or conical shape, adapted to receive the stem of the yoke-bracket and the pendant and sufficiently wide to allow them to assume any angle with respect to the vertical center of the base in the swinging movements upon the gimbals e e' of the lamp and its immediate supporting connections, which are thus kept vertical, while its base partakes of the movements of the vessel, &c., by which it may be carried. It may be here remarked that, while the construction of the frame and its connection with the base, as shown, is believed to be the best suited to all the exigencies of the use of the lamp, other constructions may be adopted without necessarily departing from this part of the invention, which consists, essentially, in mounting

the lamp so that it may have universal movement for adjusting it from the yoke-bracket to different positions for directing the rays from the lamp to a distance, as well as adapting the lamp to automatically keep a vertical position during any change in the position of its base.

The lamp may be adjusted by hand or automatically to direct the rays of light in any direction, either in a vertical or horizontal plane. Thus the annular frame D is provided with a worm-wheel 30 at one of its trunnions, that is engaged by a worm at the end of a vertical rod 31, the lower end of which carries a toothed wheel 32, adapted to be engaged by either one of a pair of pawls, according to the direction to be imparted to the wheel and shaft, operated by energizing either one of a pair of solenoids g' , carried by the yoke bracket B, the general construction of which solenoids, being similar to other solenoids used in the lamp, is shown in Fig. 4 and will be hereinafter described. By energizing either one of the pair of solenoids g' the shaft 31 will be rotated to cause the frame D, containing the lamp proper, to be moved to any inclination desired, and thus direct the rays of light to any point vertically. The lamp is moved horizontally by energizing either one of a similar pair of solenoids g^2 , also carried by the yoke-bracket B, to turn a toothed wheel 33, which, through a pinion 34, connected therewith and mounted in the bracket B, meshes with a fixed toothed edge or wheel 35 at the end of the sleeve c, containing the vertical stem of said yoke-bracket. The solenoids g^2 and connections are similar to those shown in Fig. 4, to be hereinafter described.

The lamp proper may be of any of the usual forms, with means for supporting and regulating the carbons of common form. In the present instance the pair of carbons $i f$ —the negative and positive carbons, respectively—are supported by a suitable holder E in a plane parallel with the horizontal rays thrown by the reflecting-lens F. The longitudinal axis of the carbons coincide with substantially the center of the reflecting-lens, thus presenting the arc of light at the carbon points in the most advantageous position with respect to the said lens, and so cause a very large proportion of the rays of light to be caught thereby. In this position of the carbons with respect to the reflecting-lens, with the negative carbon on the lens side, all the strongest rays of light from the electric arc are caught by the lens for the reason that the end of the positive carbon, which during use assumes a hollow or concaved form, is in itself a reflector of high power at the point where the rays of light are the most intense, reflect those rays directly onto the reflecting-lens, as indicated in Fig. 5.

The lamp-holder E is arranged, preferably, vertically across and in front of the reflecting-lens, its various parts being located in the same vertical plane, so that only a nar-

row obstruction is presented to the reflected rays of light. The holder is adapted to slide in and out of the annular frame D and is confined in place by the usual glass front D'; and it consists of a pair of rods 20 21, connected together rigidly by suitable tie-rods and by a pair of tubular bars 22 23, the latter being insulated from the rods. The major portion of the holder is supported so as to be longitudinally adjustable with respect to the annular frame D and to and from the reflecting-lens by a longitudinal guide 24, consisting of a pair of uprights projecting from the annular holder-frame E and a pair of longitudinal tie-bars secured to the uprights.

Any means may be employed for moving the holder with respect to its guide 24, either by hand or automatically, or by both. Thus the longitudinal guide supports a feed-screw 25, engaging with a nut formed in the rod 21 and actuated by a thumb-wheel on a vertical worm-rod 26, the worm of which is engaged with a worm-wheel 27, fast to the screw-shaft. The feed-screw may be moved automatically by energizing either one of a pair of solenoids g , (see Figs. 2 and 4,) according to the direction of movement to be imparted to the feed-screw. The cores of the solenoids (referring now to Fig. 4) are each provided with a pawl 40, carried by an arm 41, swinging loosely on the shaft 26 to engage a toothed wheel 28, fast to the worm-shaft. When either one of the solenoids is energized, the core first moves the pawl into engagement with the toothed wheel and then rocks the arm and pawl together to a certain distance. Soon after the arm commences to move the circuit through the solenoid is broken automatically and allows the parts to return to their former position. The positive carbon f is held by a socket 19, carried by and adapted to slide horizontally on the tubular bar 22, the said socket being formed in two portions insulated from one another, so that the current will not pass to the lamp-holder. The socket carries a contact-strip bearing against a continuous stationary conductor 18 in the lamp-circuit, extending between and insulated from the pair of rods 20 21, the current being led to said continuous conductor and by the contact-strip to the carbon in any position of the carbon-socket during the feed of the carbons. The negative carbon i is held by a socket 17, sliding in the core of a magnet-coil 16, employed for forming the arc by action of the passing current, the said coil being carried by a pair of arms 15, having horizontal rods, which enter the tubular bars 22 23 and are thereby guided during the feeding movement of the negative carbon. Both carbons are positively fed by means of a right and left hand screw-threaded rod 14, mounted in bearings in the lamp-holder E, the left-hand threaded portion engaging with one of the arms 15, supporting the negative carbon, while the right-hand threaded portion engages the socket 19 of the positive carbon. This screw-threaded rod 14

is provided with a worm-wheel 13, that is engaged by a worm 12 on a vertical operating-rod 11, mounted in the lamp-holder frame, having at one end a thumb-wheel for hand operation and on the opposite end a toothed wheel 10 for automatic operation by a pawl moved upon the energizing of a coil h of the usual form, which may be called the "feed and resistance coil."

10 No detailed description need be given of the circuits through the lamp, as they will be arranged in the ordinary way.

While the arrangement of the carbons with respect to the reflecting-lens is such as to transmit substantially all of the stronger rays of light against said lens, it has been deemed best, in order to save any other rays that might escape the lens, to provide a front reflector I immediately adjacent to and in front of the 15 carbon points. This front reflector is of curved form, encircling the positive carbon f and supported in position so that those rays of light which would naturally proceed directly to the front are caught by the reflector 20 and returned to the reflecting-lens.

In practice it will be found advantageous to adapt this front reflector for signaling purposes, and to this end this reflector is made movable with respect to the points of the carbons, so that it may be moved to obstruct the transmission of the rays of light from the arc to the reflecting-lens. While there are many ways of mounting this reflector so that it may be moved for this purpose, in the present instance the reflector is formed of two quarter-spheres 2, each mounted on vertical pivots 1 to permit the portions of the reflector to move from the position shown in full lines in Fig. 3 into the position indicated in dotted lines 35 in said figure. This movement of the front reflector may be effected by hand, but is preferably accomplished automatically by providing a magnet k , located at the upper end of the lamp-holder frame, (see Fig. 1,) that acts 40 upon an armature 8, carried at one end of a lever 9, pivoted to the frame, the opposite end of which is of duplex form, each portion engaging with one portion of the front reflector. From this construction it results that when 45 the magnet k is energized the armature will be attracted and the lever 9 rocked, thereby swinging each portion of the front reflector on its pivot into the dotted position shown in Fig. 3, and upon breaking the circuit including said magnet the armature will return and the portions of the front reflector will also return to their normal position. The periods of time between each movement of the reflector and the duration of the obstruction of 50 light from the reflecting-lens may be readily employed for signaling, by means of the lamp, to a distance.

While the mode of supporting the lamp shown in Fig. 1 may in some cases be preferable, it is obvious that the mode shown in Fig. 6 and now to be described has some advantages over it. In this modified form the lamp

is suspended at the upper end of an arched frame B' , so that it may be free to assume any position with respect to the frame during any change in the position of the frame or of the frame-base C , in which the arched frame is mounted to rotate horizontally, if desired. The annular frame D , carrying the lamp, is, as before, hung by its trunnions in the yoke-bracket B , that is suspended by its central stem b in one of a pair of gimbals $e e'$, mounted at the end of the arched frame B' . Between the end of the stem and the inner gimbal are interposed anti-friction rolls, so as to form a ball-bearing d for the free rotation of the yoke-frame and lamp with respect to frame B' . The inner gimbal is sleeved to surround the stem and at its lower end carries a toothed wheel 35, that is engaged by a pinion 34, a toothed wheel 33 connected with which is operated by the solenoid g' , all as in the structure previously described. The annular frame, with the lamp, is inclined to various degrees from its vertical position automatically by the solenoid g' , acting through the worm-shaft 31 and worm-wheel 30, fast to one of the trunnions of the annular frame D , as before described.

In using the term "lens" I do not wish to be understood as excluding the idea that a surface reflector of proper shape may be employed as the equivalent for some purposes of the part F.

What is claimed is--

1. The combination of a case or drum, a lens mounted therein, and an arc light and its frame supported by said drum with the carbon pencils parallel with the axis of the lens, substantially as set forth.

2. A lens having a central aperture, combined with an arc light having its carbon-supporting frame projecting independently of the lens into said aperture, the negative electrode being adjacent to the lens, substantially as set forth.

3. In a search-light, the combination, with the reflecting-lens, of the carbons supported in front thereof, and a removable reflector to obstruct the rays of light from the arc to the reflecting-lens, substantially as described.

4. In a search-light, the combination, with the reflecting-lens, of the carbons supported in a line parallel with the rays of light from said lens, and a front reflector surrounding one of the carbons in front of the points thereof, substantially as described.

5. In a search-light, the combination, with the reflecting-lens, of the carbons supported in a line parallel with the rays of light from said lens, and a front reflector movable from a position in front of the points of the carbons to a position behind them, substantially as described.

6. In a search-light, the combination, with the reflecting-lens, of the carbons supported in front thereof, a movable reflector to obstruct the rays of light from the arc to the reflecting-lens, and a magnet and connec-

tions for moving said reflector, substantially as described.

7. In a search-light, the combination, with the reflecting-lens, of the carbons supported 5 in front thereof, and a reflector formed of two parts, each movable from a position in front of the carbon points to a position behind them, substantially as described.

8. In a search-light, the combination, with 15 the reflecting-lens, of the carbons supported in front thereof, a reflector formed of two curved parts, each adapted to oscillate on pivots to and from a position in front of the carbon points, substantially as described.

15 9. In a search-light, the combination, with the lamp and its reflecting-lens, of an annular frame containing the same and having trunnions, a worm-wheel secured to one of the trunnions, a yoke-bracket supporting the 20 trunnions, a worm, and connections with a magnet-coil carried by the yoke-bracket for moving said frame and adjusting the lamp to different positions, substantially as described.

10. In a search-light, the combination, with 25 the lamp and its reflecting-lens, of a yoke-bracket supporting the same and mounted to rotate on a central stem, a stationary gear surrounding said stem, a pinion carried by the yoke-bracket, and connections with a mag- 30 net-coil for moving said yoke-bracket and adjusting the lamp to different positions, substantially as described.

11. In a search-light, the combination, with 35 the lamp and its reflecting-lens, of an annular frame containing the same, a yoke-bracket supporting said frame in trunnion-bearings and having a central spindle, magnet-coils, and connections with the frame and with the yoke-bracket carried by the latter for moving 40 the same and adjusting the lamp to different positions, substantially as described.

12. In a search-light, the combination, with

the lamp and its reflecting-lens, of the annular frame, the carbon-holder frame removable from the annular frame, and an adjusting 45 means for and forming part of said holding-frame to vary the carbon points with respect to the reflecting-lens, substantially as described.

13. The combination of the carbon-holder 50 frame having tubular guide-bars, a socket for one of the carbons slidable on one of the guide-bars, a socket for the other carbons, having guide-rods slidable in said tubular bars, and a right and left handed screw-rod connecting 55 said sockets for moving them simultaneously, substantially as described.

14. In a search-light, the combination, with the annular frame containing the lamp and its reflecting-lens, of a yoke-bracket supporting said annular frame, a pair of gimbals supporting said bracket, and a pinion and toothed wheel for rotating said frame and bracket irrespective of the gimbals, substantially as 60 described.

15. The combination, with the lens, of a lamp-holder frame projecting into or across the lens, having bearings for holding the carbons at right angles to the frame, substantially as described.

16. The combination, with the lens, of a vertical lamp-holder frame extending across the lens, having bearings for holding the carbons and supporting the carbon-feed screw at right angles to the frame, substantially as 70 described.

In testimony whereof I have set my hand, this 29th day of May, A. D. 1891, in the presence of two witnesses.

NELSON WEEKS, JR.
